I. D. HRENCZUK,
TOOL HANDLE,
APPLICATION FILED FEB. 21, 1922.

1,431,805.

Patented Oct. 10, 1922.

UNITED STATES PATENT OFFICE.

IWAN D. HRENCZUK, OF BOSTON, MASSACHUSETTS.

TOOL HANDLE.

Application filed February 21, 1922. Serial No. 538,163.

To all whom it may concern:

Be it known that I, IWAN D. HRENCZUK, a citizen of Ukraine, residing at Boston, in the county of Suffolk and State of Massachusetts, have invented certain new and useful Improvements in Tool Handles, of which the following is a specification.

This invention relates to certain new and useful improvements in tool handles, and 10 has particular reference to a handle provided with a reversible socket wrench, the outer end of the handle being provided with a socket for the reception of a tool blade such as a screw driver blade or auger.

15 The invention embodies in a tool handle of the type above set forth, the provision of a reversible socket wrench in the handle with adjusting screws carried by the handle and associated with the socket wrench mechanism for controlling the operating direction of movement thereof.

20 A further object of the invention is to provide a removable blade for a tool handle wherein a socket member carried by the tool handle adjustably receives the blade in a manner to vary the projecting length of the blade with respect to the socket member in the tool handle.

25 With the above general objects in view and others that will appear as the nature of the invention is better understood, the same consists of the novel form, combination and arrangement of parts hereinafter more fully described, shown in the accompanying drawing and claimed.

30 In the drawing, wherein like reference characters designate corresponding parts throughout the several views,

Figure 1 is a longitudinal sectional view 40 taken on line I—I of Fig. 2 showing the screw operated ratchet dogs engaging the ratchet member of the socket wrench and the extensible blade carried by the tool handle.

Figure 2 is an edge elevational view, 45 partly in section showing one of the ratchet dogs with the socket wrench engaging a member, as illustrated by dotted lines,

Figure 3 is a longitudinal sectional view 50 of the tool associated with the handle showing the socket member for attachment to the handle and the blade resiliently mounted in the socket member with the screw pin for holding the blade in its adjusted position, and

Figure 4 is a side elevational view of the 55 blade and carrying the socket member.

Referring more in detail to the accompanying drawings, there is illustrated a tool handle embodying a body portion 1 having a relatively large elongated side opening 60 socket 2 therein with a face plate 3 closing the open side of the socket and extending over the entire adjacent face of the handle. As shown in Figs. 1 and 2, the outer end of the handle 1 is provided with a polygonal 65 socket 4 for the reception of a tool blade to be later described.

A ratchet controlled socket wrench is carried by the handle 1, the socket wrench having bearing ends 5 journaled in the bottom wall of the socket 2 and the opposite side plates 3, the socket wrench extending transversely of the handle with the polygonal bore 6 formed therein registering with the openings 7 in the handle 1 and side 75 plates 3. The socket wrench extends transversely of the outer end of the socket 2 and the external face thereof is provided with ratchet teeth 8 disposed in said socket.

Spring pressed dogs are associated with 80 the socket wrench, each dog 9 being pivotally mounted intermediate its ends upon a pin 10 supported in the handle as shown in Fig. 2, the outer ends of the dogs engaging the ratchet teeth 8 upon the socket wrench 85 at opposite sides of the vertical axis thereof. As shown in Fig. 1, a coil spring 11 extends between the inner ends of the dogs 9, normally to separate the inner ends and force the outer ends thereof into engagement with 90 the ratchet teeth 8. The inner end of each dog carries a socket member 12 within which an adjusting screw 13 is received, the screw being threaded through the opposite edge walls of the handle for shifting the inner 95 ends of the dogs against the tension of the spring 11 and to selectively disengage the outer ends of either dog from the ratchet teeth 8.

From the above detail description of the 100 socket wrench, it is believed that the construction and operation thereof will at once be apparent, it being noted that either of the screws 13 may be operated for shifting a dog 9, as shown by dotted lines in Fig. 105 1 to a disengaging position with respect to the socket wrench, at which time the dog 9 remaining in engagement therewith will

cause the working movement of the socket wrench in one direction with the dog 9 escaping the teeth when movement of the handle in the opposite direction is effected. 5 The spring 11 normally forces the inner ends of the dogs apart with the outer ends thereof into engagement with the ratchet teeth 8. Upon operating either of the screws 13, the desired dog 9 is placed in 10 operative engagement with the wrench socket member, and the socket member is accordingly locked to the tool handle when the handle is shifted in the proper direction.

15 A tool blade of any preferred type is associated with the outer end of the handle, the elongated socket member 14 carrying a polygonal base block 15 that is received in the socket 4 of the tool handle slidably receives the tool blade 16, a coil spring 17 being anchored at opposite ends as at 18 and 19 to the block 15 and the inner ends of the blade 16, respectively. To hold the blade 16 in its adjusted position, a side face 20 thereof is provided with a plurality of base depressions or sockets 20 for the reception of the screw pins 21 threaded through the side wall of the socket member 14, as shown in Fig. 3. The spring 17 has a tendency 25 normally to move the tool blade 16 inwardly of the socket member 14, while the screw pin 21 holds the tool blade in its adjusted position. It will therefore be seen that the blade 16 may be projected the desired distance to accommodate the tool to 30 various classes of work, while the connec-

tion between the tool blade and the socket member 14 is of a rigid character to render the device highly practical.

It is believed that the construction of tool 40 handle disclosed in this application will be readily understood by those skilled in the art, it being noted that the wrench socket, as shown in Fig. 2 is illustrated as engaging an object as A for turning a portion thereof, as a nut or like device, and while there is herein shown and described the preferred embodiment of the present invention, it is nevertheless to be understood that minor changes may be made in the invention without departing from the spirit and scope thereof. 45

What is claimed as new is:—

50 A tool of the type described, comprising a body portion having a side opening socket 55 therein, a side plate for closing the socket, a socket wrench journaled in the handle and extending transversely of said socket, a pair of opposed dogs pivotally mounted in the handle socket in engagement with the 60 socket wrench, a single expansion spring interposed between the inner ends of the dogs, and a screw pin for engaging each of the dogs to shift the same to a position spaced from the wrench socket against the tension 65 of the spring with one of the dogs remaining in ratcheting engagement with the wrench socket.

In testimony whereof I affix my signature.

IWAN D. HRENCZUK.
